E. A. BENDIXON

MUSICAL TOY

Filed August 9, 1924

Patented Mar. 2, 1926.

1,575,032

UNITED STATES PATENT OFFICE.

ELMER A. BENDIXON, OF CHICAGO, ILLINOIS.

MUSICAL TOY.

Application filed August 9, 1924. Serial No. 731,007.

To all whom it may concern:

Be it known that I, ELMER A. BENDIXON, a citizen of the United States, and a resident of the city of Chicago, in the county of Cook and State of Illinois, have invented a certain new and useful Improvements in a Musical Toy; and I do hereby declare that the following is a full, clear, and exact description of the same, reference being had 10 to the accompanying drawings, and to the numerals of reference marked thereon, which form a part of this specification.

This invention relates to musical toys more particularly of the type in which a handle is rotated to produce the desired sound.

It is an object of the invention to provide a simple, cheaply constructed musical toy.

Other and further important objects of 20 this invention will be apparent from the disclosures in the accompanying drawings and specification.

The invention (in a preferred form) is illustrated in the drawings and hereinafter 25 more fully described.

Figure 1 is a side elevation in section of the device.

Figure 2 is a side elevation of the device.

Figure 3 is a bottom plan in section showing the pick and the reeds.

Figure 4 is a detail side view of the sheet, reeds and pick.

Figure 5 is a sectional view of Figure 4.

Figure 6 is a detail view showing the pick 35 engaging the reeds when the handle is moving in a clockwise direction.

As shown on the drawings:

As shown in Figure 1, the handle 1 and the pick 2 are formed integrally on the same 40 piece of wire. The plate 6 (Figure 3) is cut to form a plurality of reeds 3 which are picked by the pick 2 when the latter is moved about its axis by the rotation of the handle 1. The stem connecting the pick 2 and the handle 1 extends through the bushing 7, the upper cavity of the casing 5 and out through a hole in the top of said casing. A collar 12 with set screws prevents the lowering of the handle 1 or the pick 2.

The bushing 7 (Figure 5) holds the 50 washer 8 tightly down upon the plate 6 which has formed upon it the circular ridge 13 and clamps said plate against the shoulder 9. The washers 10 and 11 55 strengthen the sheet 4 which is preferably made of pressed board. The function of the

circular ridge 13 is to provide a pivotal point about which the reeds 3 bend when plucked by the pick 2. The bushing 7 forms a bearing for the stem of the pick 2 as well as a 60 means for clamping the plate 6 to the shoulder 9 and the sheet 4.

More specifically the pick 2 comprises a short upwardly bent portion 2^a and somewhat longer outwardly and 65 downwardly bent portion 2^b, and an upwardly and inwardly bent portion 2^c; all of said portions being formed successively from the lower end of the stem connecting the handle 1 and said pick. The 70 portions 2^a and 2^b are substantially in the same vertical plane as the stem but the portion 2^c is slanted somewhat to the left out of the vertical plane as shown in Figure 6, 75 for a purpose which will be apparent from the operation hereinafter described.

Upon the rotation of the handle 1 in an anti-clockwise direction (Figure 3) the reeds will be engaged by the lower side of the pick portion 2^c (Figure 5) and upon the further rotation each reed will in turn be disengaged by said portion, said reed sliding off the under side of said portion near the juncture of the latter and the portion 2^b producing a musical note, the character of the note depending upon the length of the particular reed. By rotating the handle 1 in a clockwise direction (Figure 3) the reeds will in turn be engaged by the upper side of the portion 2^c and slide off the 80 upper end thereof producing musical notes in the same manner as before. It will be seen that when the handle 1 is rotated in a clockwise direction as viewed in Figures 1 or 2 the pick as viewed in Figure 3 will be 85 moving in an anti-clockwise direction.

The pick and the handle being formed by a single wire tends to greatly reduce the cost of the device. This device produces musical notes when the handle is rotated in either 90 direction. By use of the circular ridge 13 the reeds are always bent at the same point, and a better elasticity and a better tone are obtained.

I am aware that numerous details of construction may be varied through a wide range without departing from the principles of this invention, and I therefore do not 95 purpose limiting the patent granted otherwise than necessitated by the prior art.

I claim as my invention:

1. A musical toy comprising a handle, a

105

100

110

stem and a single pick finger secured on said reeds 5 and a plurality of reeds adapted to be engaged by said pick when the latter is moved in either direction, said finger being constructed so as to engage with said reeds when moved either forwardly or reversely.

2. A musical toy comprising a handle, a pick connected to said handle, a plate having a circular ridge, a shoulder engaging 10 said ridge, a washer engaging said plate and means for clamping said plate at said ridge between said washer and said shoulder, and a plurality of reeds on said plate surrounding said ridge and adapted to be engaged by 15 said pick.

3. A musical toy comprising a handle, a pick on said handle, a plate having an annular ridge stamped therein, means for clamping 20 said plate at said ridge, and a plurality of reeds integral with said plate adapted to be engaged by said pick, said reeds being distributed about the periphery of said plate outwardly of said ridge.

4. A musical toy comprising a metal housing having a flat bottom, a sheet parallel to 25 said bottom and secured to said housing, a shoulder, a plate having a circular ridge and a plurality of reeds integral therewith, a washer and means for clamping said sheet, shoulder, 30 plate and washer together, said means comprising a bushing, a stem extending through said bushing and top of said housing, a handle on one end of said stem outside of said housing and a pick on the 35 other end of said stem, said pick being adapted to pick said reeds upon being revolved in either direction, said handle and said pick being integral with said stem.

5. A musical toy comprising a metal housing having a flat bottom, a sheet parallel to 40 said bottom and secured to said housing, a shoulder, a plate having a plurality of

reeds integral therewith, a washer and means for clamping said sheet, shoulder, 45 plate and washer together, said means comprising a bushing, a stem extending through said bushing and top of said housing, a handle on one end of said stem outside of said housing and a pick on the other end of said stem, said pick being adapted to pick 50 said reeds upon being revolved in either direction, said handle and said pick being integral with said stem.

6. A musical toy comprising a metal housing having a flat bottom, a sheet parallel 55 to said bottom and secured to said housing, a shoulder, a plate having a plurality of reeds integral therewith, a washer and means for clamping said sheet, shoulder, 60 plate and washer together, a stem extending through said washer, plate, shoulder, sheet and top of said housing, and a handle and pick integral with said stem.

7. A musical toy comprising a metal housing having a flat bottom, a sheet parallel 65 to said bottom and secured to said housing, a shoulder, a plate having a plurality of reeds integral therewith, a washer and means for clamping said sheet, shoulder, 70 plate and washer together, a stem extending through said washer, plate, shoulder, sheet and top of said housing, a handle and pick integral with said stem, said pick being adapted to engage said reeds upon being revolved in either direction.

8. In a musical toy, a casing, vibratable elements therein, a handle rotatably mounted in the casing and a single pick finger on the handle for actuating the vibratable elements when the handle is rotated in either direction.

In testimony whereof I have hereunto subscribed my name.

ELMER A. BENDIXON.
